CABLE GRIP OR THE LIKE

Edgar E. Kellems, New York, N. Y., assignor to
 Kellems Products, Inc., New York, N. Y., a corporation of New York

Application September 18, 1936, Serial No. 101,528

6 Claims. (Cl. 24—123)

This invention relates to a cable grip involving the use of an open mesh woven wire tube and a draft head rigidly secured to one end thereof and refers more particularly to the draft head and to the method of applying the same to the end of the woven wire tube.

In grips of this character, the wire strands are usually interwoven spirally around a common axis from end to end so as to cross each other diagonally, and the main object of the present invention is to cast the draft head around and upon one end of the woven wire tube in such manner that the crossing portions of the strands at that end will be imbedded and concealed within the draft head diagonally to the line of draft and thereby to secure a stronger and more reliable connection between the draft head and woven wire tube than has heretofore been practised.

Another object is to provide the draft head with a central lengthwise opening and a draft bolt journaled therein and operatively connected thereto for drawing the grip and object to which it is attached endwise and at the same time permitting relative rotation of the draft head and bolt.

A further object is to enable two gripping devices to be swivel-connected to each other end to end for relative rotation by one and the same draft bolt as for example, when replacing old elevator cables with new ones which latter are usually unwound from a reel thereby causing more or less relative rotary motion of the two cables.

Other objects and uses relating to specific parts of the device or different steps in the process of applying the head to the woven wire tube will be brought out in the following description.

In the drawings:—

Figure 1 is a side elevation of a pair of cable grips provided with my improved draft heads connected to each other by a draft bolt.

Figure 2 is an enlarged longitudinal sectional view through the adjacent ends of the gripping elements taken on line 2—2, Figure 1.

Figure 3 is a longitudinal sectional view of the development of one of the draft heads and adjacent ends of the strands of the woven wire tube imbedded therein.

Figure 4 is a sectional view of the mould sections with the adjacent end of the woven wire tube therein ready for casting the draft head upon and around the crossing portions of the enclosed strands.

Figure 5 is a face view, partly in section, of

one end of one of the cable grips together with an eye attached to the outer end of the draft bolt which is swiveled in the head.

Figure 6 is a sectional view of a solid cast metal draft head with the adjacent ends of the strands of the woven wire tube imbedded therein in which the head is provided with an integral draft eye.

Figure 7 is a face view of my improved draft head for woven wire grips as used in connection with an electric plug.

Figure 8 is a side view, partly in section, of the device shown in Figure 7.

Figure 9 is a perspective view of one end of the gripping device shown in Figure 7, having an oval head.

Figure 10 is a perspective view similar to Figure 9 showing an angular head.

Figure 11 is a face view similar to Figure 7 in which both ends of the woven wire grip is provided with heads cast thereon.

As shown in Figures 1, 2, 3 and 5, each gripping device comprises an open mesh woven wire tube 1 and a cast metal head 2 in which the strands of one end of the woven wire tube 1 are imbedded during the process of moulding in a manner presently described.

The woven wire tube 1 is similar in some respects to that shown in my Patent No. 1,670,543, May 22, 1928, in that the strands are interwoven spirally around a common axis in such manner that those of the cable-receiving end of the tube are returned toward its opposite end to form a series of loops in uniformly spaced relation about said axis, while the remaining portions of the strands cross each other diagonally with reference to the line of draft but instead of bunching the draft ends of the strands they are cut off in a plane at substantially right angles to the axis of the tube so that the draft end of the latter maintains its normal diameter, depending somewhat upon the size of the mandrel upon which the tube is woven and also upon the size of the object to which the gripping device is to be applied.

Under these conditions, the major portion of the length of the woven wire tube will expand by endwise compression to enable the tube to be easily fitted over and upon the cable or other object but automatically distends itself endwise to contract upon said cable or other object preparatory to drawing the latter endwise through an underground conduit or overhead support or for any other purpose to which the cable grip may be applied.

In other words, the mere act of extending the main body of the cable grip endwise causes the strands to contract upon the cable with increasing force proportionate to the force of draft applied to the head 2.

As previously stated, the draft head 2 is made of cast metal, preferably of non-corrodible character, such for example as aluminum alloy of a hard nature when cooled but capable of being 10 injected into the mould by any suitable die moulding apparatus when molten.

In Figure 4 I have shown a mould consisting of separable sections 3 and 4 and a core section 5 supported centrally within the mould and 15 having one end provided with an enlarged head or flange 6. This mould is provided with a cylindrical chamber 7 of slightly greater diameter than the adjacent end of the woven wire tube 1 and of sufficient length to receive a limited number of 20 the crossing portions of the strands at the corresponding end of the tube.

One end of the mould is provided with a circular opening 9 of about the same diameter as the external diameter of the adjacent portion 25 of the woven wire tube so that its walls may engage the outer periphery of the tube. The head or flange 6 of the core section 5 is also circular and of about the same diameter as the interior diameter of the woven wire tube to closely engage 30 the same while the remaining reduced portions of the core section 5 are preferably cylindrical and of appreciably less diameter than the interior diameter of the adjacent portion of said tube for forming a central opening as 8 in the draft head 2. 35 The reduced cylindrical portion of the core section 5 extends through a corresponding opening 9' in the adjacent end of the mould to effectively close the same and thereby to prevent the escape of the molten metal therethrough 40 when the core is in place, the upper section of the mould being provided with an inlet sprue 10 through which the molten metal may be introduced into the chamber 7.

When preparing to cast the head 2, the core 45 section 5 is first inserted into the adjacent end of the woven wire tube 1 a distance corresponding approximately to the length of the chamber 7 after which the end of the woven wire tube with the core section 5 therein is placed in position 50 within the mould, as shown in Figure 4, so that the flange 6 will be disposed in approximately the same transverse plane as the adjacent end walls of the chamber 7, while the reduced portion of the core section 5 will extend through 55 the opening 9' and preferably beyond the outer end wall of the mould.

Under these conditions, it is obvious that the crossing portions of the wire strands within the mould chamber 7 will be held in spaced relation to the peripheral walls of said chamber and also in spaced relation to the core so that when 60 the molten metal is introduced into the chamber it will surround the crossing strands of the adjacent end of the woven wire tube to form a rigid 65 and permanent connection between the draft head and woven wire tube when the molten metal hardens.

During this casting of the draft head 2 within the mould, it is evident that certain portions of 70 the strands between the periphery of the flange 6 and adjacent end wall of the mould sections 3 and 4 will be spaced apart, thereby allowing corresponding portions as 11 of the molten metal to pass into said spaces between the periphery of 75 the flange 6 and adjacent end wall surrounding

the opening 9 of the chamber 7, thus forming an annular recess 12 in the adjacent end of the draft head for a purpose presently described.

It will be noted, however, that the amount of molten metal passing through the space between the periphery of the flange 6 and adjacent end wall surrounding the opening 9 of the chamber 7 and through the adjacent openings between the strands is negligible and does not in any way interfere with the perfect casting of the cylindrical 10 draft head 2 within the mould and around and upon the enclosed wire strands which cross each other within the chamber 7.

When the draft head is cast in the manner described upon and around the enclosed end of the 15 woven wire tube, all portions including the crossing portions of the enclosed strands, will be rigidly imbedded in the casting and that owing to the diagonal disposition of the strands within the mold during the casting operations, it is evident that when the metal has cooled it will be practically impossible to separate the head from the woven wire tube without breaking the wires which, of course, are made to withstand the strains to which they may be subjected, it being understood that each strand is generally made of two or more smaller strands each composed of a relatively large number of finer wires twisted 20 upon each other to give the desired strength and 25 elastic flexibility.

In Figure 3 is shown a sectional development 30 of the cast metal draft head with the crossing portions of the wire strands of the adjacent end of the woven wire tube imbedded therein during the casting process, thus showing that the imbedded 35 portions of the strands are diagonal to the line of draft which greatly increases the resistance to axial separation of the head and tube under the most severe tensile strains to which they 40 may be subjected.

It will thus be understood that the cast metal not only surrounds the adjacent portion of each strand but also fills the spaces between the strands, thus making the draft head a rigid 45 unitary part of the gripping device, while the remaining portions of the woven wire tube are free to be compressed axially for radial expansion 50 against the tension of the wire strands which automatically return to their normal positions when the axial pressure is relieved.

A hardened metal bearing washer 13 of about 55 the same size and form as the head or flange 6 of the core 5 is inserted in the recess 12 in the outer end of the head 2.

A draft bolt 14 is passed through the central 60 opening 8 of the head 2 and is also extended through the washer 13 and provided with a head 15 for engaging said washer, said bolt being extended some distance beyond the outer end of the head for receiving and supporting a similar 65 head 2 of another gripping device, another washer 13 and a nut 16, whereby both gripping devices 70 may be relatively rotatable upon the draft bolt 14, as shown in Figures 1 and 2.

The assembly of the coupling shown in these 75 Figures 1 and 2 is effected by placing the head 15 of the bolt 14 in a socket wrench having a handle long enough to reach through the grip body 1, and inserting the bolt through the bores 1, 8 of 80 the heads 2, 2 by passing the wrench through the cable receiving end of one of the grips. Similarly, the nut 16 is placed in another socket 85 wrench having a handle long enough to reach through the other grip body 1 so that the nut 75

can be screwed onto the threaded end of the bolt.

In case the bolt is used to connect the adjacent heads of two gripping devices, both heads will be identical in that they are cast in the same mold and each head will be provided with the annular recess 12 for receiving a washer 13, the bolt being provided with a nut or head 16 threaded thereon for holding the heads of both gripping devices 10 against axial displacement, see Figures 1 and 2.

When two gripping devices are swivel-connected to a common swivel bolt 14, as shown in Figures 1 and 2, one gripping device may be attached to one cable and the other to another 15 cable to form a continuation-coupling for said cables to be used in replacing elevator cables and analogous uses where it is desired to use one grip on one object for drawing another cable or object endwise, it being understood that when the work 20 is completed both grips may be detached from their respective objects and reused in other relations.

When a single gripping device is to be used, to draw a cable or other object endwise, an eye nut 25 or similar draft member 17 may be screwed upon the outer end of the bolt 14 and held against rotation relatively to the bolt by means of a key pin 18 so that the draft head 2 and draft bolt 14 may rotate relatively to each other in which case 30 a rope or cable may be attached to the eye 17 for drawing the cable and object engaged thereby endwise.

In Figure 6, I have shown the head 2' as cast solidly around and upon the crossing strands on 35 one end of the woven wire tube 1 and provided with an integral draft eye or loop 17' for receiving a draft cable whereby the gripping device and object engaged thereby may be drawn endwise.

In all of these devices, it will be noted that 40 the draft heads are of only slightly greater diameter than the external diameter of the woven wire tubes which, in turn, are of only slightly greater diameter than the cable or other object engaged thereby, thus permitting the gripping 45 device or devices to be used individually or jointly as continuations or couplings of the cable to enable the draft heads to be drawn through any opening capable of receiving the woven wire tube or to be drawn around drums or pulleys, as for 50 example when replacing elevator cables and the like from a reel to a drum.

The important feature of the invention, however, is to establish a rigid and permanent connection between the draft head and one end of 55 the woven wire tube in such manner that the strands of the tube are imbedded in the head diagonal to the line of draft of the gripping device, but obviously the mold in which the draft heads are cast may be varied and other changes 60 made in the detail construction of the head without departing from the spirit of the invention.

When the head 2 is cast upon the ends of the woven wire tube within the mold and properly hardened by cooling, the molds are separated to 65 release the head therefrom, thus permitting the withdrawal of the woven wire tube with the head cast thereon together with the core 5 which may then be driven endwise into the woven wire tube and displaced from the other end thereof for 70 reuse in casting other heads in the same mold.

In Figures 7 to 11 inclusive, I have shown my invention as applied to an electric plug and an electric cable attached to the terminals thereof for holding the plug and cable against relative 75 separation and also for relieving connections be-

tween the cable and terminals from excessive strains resulting from endwise pull upon the plug or cable.

This device is particularly useful in connection with any electric cable carrying a plug at one or both ends adapted to be frequently attached to and removed from sockets of various electrical fixtures such as sadirons and the like and also for wall plugs and similar uses where the connections between the cable and plug are subjected to more or less severe endwise strains tending to loosen or break said connections.

The plug as 20 is of standard make and is preferably composed of opposite sections 21 and 22 secured together face to face by means of one 15 or more clamping bolts 22 and having their meeting sides provided with suitable recesses for receiving electric terminals, not shown, said sections being provided near one end with opposed registering recesses 23 and 23 and a central opening 24, the latter serving to receive one end of an electric cable 25.

The wires of this cable are preferably encased in a flexible insulating material and are attached at one end to the electric terminals in the usual 25 manner not necessary to herein illustrate or describe.

Suitable means is provided for holding the cable and plug against relative endwise separation and thereby to relieve the binding connections 30 between the wires and terminals of the plug from excessive strains resulting from pulling the plug from the socket by means of the cable or other cause for such strains.

For this purpose, I have provided a woven wire 35 tube 1' similar to that previously described in that the wire strands of at least one end of the woven wire tube are incorporated in a cast metal head 26 of substantially the same form and size as the combined grooves 23 in the plug 20 when 40 the sections thereof are clamped together.

This cast metal head 26 is provided with a central opening for receiving the adjacent end of the cable 25, the opening and cable being of approximately the same diameter to allow the cable to be 45 easily inserted therethrough, as shown in Figures 7 and 8.

The woven wire tube 1' with its cast metal head 26 is placed over and upon the adjacent portion of the cable 25 in such manner that when 50 the tube is extended endwise under its own tension it will automatically tighten upon the cable.

When assembling the plug upon the adjacent end of the cable with the sections thereof separated, the wires in the cable will be attached 55 in the usual manner to the terminals of the plug while the head 26 will be seated in the groove 23 of one of the plug sections. The other section is then placed in position to cause the head to enter its groove 23 followed by the clamping of the two 60 sections together through the medium of the bolt 22.

Under these conditions, the woven wire tube 1' will extend outwardly some distance from the plug 20 along and upon the cable 25 to firmly but 65 releasably grip the same and to form a convenient means whereby the cable may be drawn endwise to remove the plug from its socket without in any way overstraining the connections of 70 the cable wires with the plug terminals.

The head 26 may be oblong as shown at 26' in Figure 9, or angular as shown at 26'' in Figure 10, the object of which is to prevent relative turning of the woven wire tube and plug when the 75

head is fastened in place between the opposite sections of the plug.

In Figure 11, I have shown the outer end of the woven wire tube 1" as provided with a cast metal head 27 similar to the head 26 in that the adjacent ends of the wire strands are incorporated thereon during the process of casting.

This head 27 in addition to the main body of the woven wire tube serves as a handle by which the plug may be withdrawn from the socket without overstraining any of the wire connections with the terminals of the socket.

It is evident, however, that this device may be used in many other relations with slight alterations within the scope of the present invention.

What I claim is:-

1. A cable-grip comprising a cast-metal draft-head having a central lengthwise opening therethrough, a woven-wire tube having one end imbedded in the draft-head between the inner and outer surfaces thereof so that the individual wires of the tube are completely enveloped therein, and a draft-member rotatably mounted in said opening.
2. A cable grip comprising a tubular draft-head, an open-mesh woven-wire tube having one end imbedded in the head between the inner and outer surfaces thereof so that the individual wires of the tube are completely enveloped therein, and a draft-member journaled in said head.
3. A cable grip comprising opposed co-axial and relatively rotatable draft heads having aligned central openings, a bolt connecting said heads and swiveled in at least one of said openings to per-

mit relative turning of the heads, and opposite open-mesh wire-strand tubes each having one end imbedded in the corresponding head between the inner and outer surfaces thereof so that the individual wires of the tube are completely enveloped therein.

4. A cable grip comprising a tubular draft-head having an annular recess in one end, woven wire tube having the crossing strands of one end imbedded in said head so that the individual wires of the tube are completely enveloped therein, a bearing ring seated in said recess within the adjacent portion of the woven-wire tube, and a draft-member passed through the draft-head and engaged with said ring.

5. A cable grip comprising a tubular draft-head, a woven-wire tube having one end imbedded in said draft-head so that the individual wires of the tube are completely enveloped therein, a bearing-ring within said end and engaging the inner end of the draft-head, and a draft-bolt engaging said ring and extended outwardly through the draft-head.

6. A cable grip comprising opposed co-axial and relatively rotatable draft heads having aligned central openings, washers seated against the outer ends of the heads, and a bolt passed through both heads and washers and having its opposite ends provided with heads engaging the adjacent washers, said heads and bolts being relatively rotatable, and a woven expandable and contractible tubular gripping member connected with each head, and each having an end embedded therein.

EDGAR E. KELLEMS.
